UNITED STATES PATENT OFFICE

CHARLES D. HOWENSTINE, OF NORTH CHARLEROI, PENNSYLVANIA

MACHINE FOR COUNTING AND DELIVERING COINS

Application filed June 5, 1931. Serial No. 542,273.

Among the objects which I have in view are the following. The provision of new and improved means whereby coins or tokens of a selected character may be counted and/or delivered from a mass of coins.

The provision of means whereby coins or tokens of a selected character may be delivered in groups of a selected number.

The provision of means whereby coins or tokens of a selected character may be delivered in groups of a selected number and the total number of coins in the plurality of groups to be formed may be simultaneously counted.

Other objects will appear from the following description.

For these and other purposes I have invented the machine whose principles are hereinafter explained.

In the accompanying drawings, wherein I have illustrated a practical embodiment of the principles of my invention, Fig. 1 is a side elevation of the apparatus with one of the side walls of the boxing removed, the selective arm being shown set to count and deliver fifteen coins, such as pennies.

Fig. 2 is a broken side elevation showing the side wall which is omitted in Fig. 1 and also showing the setting arm.

Fig. 3 is a view similar to Fig. 1 but parts being omitted and the mechanism shown as it is when a predetermined group of coins has been counted and delivered.

Fig. 4 is a section of the apparatus taken along the irregular line 4-4 in Fig. 5.

Fig. 5 is a plan view of the mechanism with the enclosing boxing removed except for a broken portion of one of the side walls.

Fig. 6 is a horizontal section taken along the line 6-6 in Fig. 5.

Fig. 7 is a detail in section taken along the line 7-7 in Fig. 5.

Fig. 8 is a broken front elevation showing the coin-lever, also shown in Fig. 5, but adjusted for actuation by a coin of smaller diameter, such as a dime.

Fig. 9 is a partial rear elevation of the same.

Fig. 10 is a broken rear elevation showing the arcuate slot through which the means for

shifting the axis of the coin lever protrudes so that the coin lever may be adjusted for different coins.

Referring to the drawings, the mechanism is enclosed in a metal boxing comprising a bottom 1, the side walls 2 and 2a, rear wall 3, the top 4 which does not extend as far forwardly as the bottom and the lower front wall 5. The lid 6, which is hinged at its bottom edge, as will later be more fully described, when closed occupies the upwardly and rearwardly inclined position shown in Fig. 1 but which when the machine is in use is opened downwardly in the inclined position shown in Fig. 4. A suitable support, such as the hinged leg 7, is provided to support the lid in its open position.

8 represents a cup-shaped housing which is circular in shape having a flat bottom and a low perimetral wall 8a. This housing is supported in the upwardly and rearwardly tilted or inclined position shown in Fig. 4, in the boxing in any convenient manner. Thus I have indicated a screw 9 extending through the side wall 2 and screwed into a threaded hole 10 in the wall of the housing. A like but longer screw is inserted through the other side wall 2a into a like hole in the other side of the housing. Also, as will later appear, the housing is further supported relative to the boxing by its coin delivery spout 11 which extends through the rear wall 3.

12 represents a circular disk which is revolvably mounted in the housing 8, being mounted on the front and upper end of a shaft 13 which is journaled in a bearing formed in the center of the housing. On the rear end of the shaft 13 is fixed the bevelled gear 14 meshing with a bevelled pinion 15 mounted on a cross shaft 16 which is journaled in bearings 16a mounted on the back of the housing. One end of the shaft 16 is provided with a crank 17 at the outside of the side wall 2a for rotating the shaft 16 and thus rotating the disk 12. The rotation of the disk is clockwise in Fig. 5.

The disk 12 is provided at its perimeter with a plurality of spaced apart arcuate notches 18 whose rear edges, that is the edges which trail as the disk is rotated, are bevelled

off as at 19 to permit a coin, stacked on or adhering to the coin which is engaged in a notch, to slip off onto the exposed face of the disk as the notch moves under the guard 5 plate which will be later described.

To the right of the top of the housing 8 the bottom or rear wall of the latter is provided with an aperture or coin-port 20 to which the inner end of the delivery spout 11 10 is connected, the spout being fixed to the housing and extending, as has been explained, through an opening in the rear wall 3, the brackets 21 being attached to the spout and to the rear wall to assist in supporting the 15 housing.

The port 20 is so positioned that as the disk is rotated and after a notch 18 has attained its highest position it passes the port and the 20 coin carried along by the notch will drop by gravity, owing to the tilt of the housing and disk, through the port 20 into the spout 11.

To maintain the coins in the notches as they are being carried along with the disk a 25 flat metal guard plate 22 is provided. This plate is secured to the wall 2a of the housing and it has an arcuate portion which covers the notched perimetral portion of the disk 12 at the upper portion of the housing and down along its right hand side. The plate is 30 spaced sufficiently from the disk to provide clearance for the coins carried by the notches and its edge is bevelled as at 23 so as to contact with the bevelled rear edges of the notches to strip off any extra coin which may be 35 stacked upon or may adhere to the coin in a notch.

The plate 22 extends through a cut away portion of the wall of the housing to the left 40 in Fig. 5 to provide a bracket for the support of certain parts of the mechanism to be later described.

24 represents a depending latch pivotally mounted on the face of the plate 22 and having its free end extending through a slot 25 in said plate to trail over the face of the moving disk 12 and by engaging with the front walls of the notches to prevent material 105 counterclockwise rotation of the disk.

26 represents the coin-lever which is pivotally mounted intermediate of its end on the cap screw 27 which extends forwardly through a vertically disposed arcuate slot 28 in the plate 22. The screw 27 is mounted on 50 the free end of a lever 29 which is pivotally mounted at its other end as at 30 against the rear face of the plate 22. Thus the axis of movement of the coin-lever may be raised or lowered for the purpose hereinafter described. 31 represents a plate pivotally mounted as by the cap-screw 32 on the front of the plate 22 and having an arcuate slot 33 eccentric to the screw 32 through which slot the cap-screw 27 extends. The upper end of 55 the plate 31 is provided with a rearwardly

curved operating finger 34 fixed relative to the plate and protruding rearwardly through an arcuate slot 35 in the rear wall 3 of the housing.

It is obvious that by taking hold of the 70 protruding end of the finger 34 the plate 31 may be shifted and thus the axis of movement of the coin-lever 26 may be adjusted vertically. The lower end of the plate 31 is bent inwardly as at 36 against the front face of the 75 plate 22 and a spring 37 coiled about the cap-screw 27 presses said plate 31 snugly against the plate 22 to prevent accidental movement of the plate 31 and shifting of the axis of the coin-lever 26.

The inner or right end of the coin-lever 26, as it is illustrated in Fig. 5, is provided with a stud-bolt 38 which extends rearwardly through a vertically elongated slot 39 in the plate 22 which slot is slightly arcuate. On 85 the rear end of the bolt 38 is mounted a roller 40 which moves in the rear of the plate 22, the top edge of the housing 8 being notched as at 41 to provide clearance for the descent of the roller.

The roller is in the path of the coins carried along by the notches 18 of the disk 12 and is engaged by said coins as they reach and pass their highest position and before they drop through the port 20 into the coin 90 spout 11.

Insomuch, as will later appear, the arc of movement of the other or outer end of the coin-lever 26 is substantially constant, provision must be made for adjusting the lever so that it will be rocked counterclockwise only by coins of the diameter selected for counting. Thus were the axis of the coin-lever constant a nickel would throw the other end of the lever farther than would a penny and a penny would throw it farther than would a dime. However by my provision for adjusting the axis of the lever vertically, I am able to arrange the lever so that it will be operated only by the coin selected and the arc of movement of the other end of the lever will remain substantially constant. Thus if the lever is adjusted for dimes it would jamb if pennies or nickels be carried into contact with the roller. Likewise a nickel would jamb a lever set for pennies. Again when the lever is set for nickels, pennies or dimes will not operate nor will a dime operate the lever when it is set for pennies or nickels.

The other and outer end of the coin-lever 120 is provided with a box 42 comprising upper and lower flanges in which is loosely held the enlarged lower and rear end of a bent lever 43 which is pivotally mounted at its angle on the inner face of a frame plate 44 secured to the left side of the housing 8 and extending upwardly and connected to the left end of the plate 22 to form a support for portions of the mechanism. The front and upper end of the lever 43 is connected by a link 45 with the 125 130

operating crank 46 of a rotary disk counting device 47 which may be of any suitable character and whose totals are visible through an opening 48 in the top 4 of the boxing.

5 Thus the counting mechanism is operated to record and/or indicate one digit every time the coin-lever is rocked counterclockwise by a coin carried past the roller by the notched disk 8. The coin lever and the bent lever are 10 given a return movement by the helical spring 49 which connects the upper end of the bent lever with a fixed point on the frame plate 44 such as the bolt 50 which extends through the frame plate.

15 As already explained by properly adjusting its axis of movement the coin-lever may be arranged to be operated by a coin of the diameter which is selected for counting. Thus if the coin lever 22 be adjusted for dimes, a nickel or penny carried by the notched disk 12 will be too large and the roller cannot move upwardly far enough to allow the coin to pass by it. Therefore the disk will be jammed against movement. On the other hand if the 20 coin carried by the notched disk be of too small diameter to raise the roller sufficiently to enable the coin-lever to operate the bent lever 43, as would be the case where the fulcrum plate is adjusted to a larger coin, then the 25 passing coin will not be counted by the counting device.

In the drawings I have shown the coin-lever adjustable for dimes, nickels and pennies, but it will be understood that the selective range 30 of the coin-lever may be enlarged to include any reasonable number of kinds of coins, tokens and the like which may be desired.

The mechanism provided for delivering a predetermined number of coins is as follows. 35 51 represents a tubular stud whose inner end is screwed or otherwise secured in a hole 52 in the frame plate 44 and a circular disk 53 is rigidly mounted on said stud in spaced relation to the frame plate. 54 represents a 40 ratchet wheel rotatably mounted on the stud 51 between the frame plate and the disk, a spring 55 being coiled about said stud with its ends connected to the stud and to the outer face of the wheel, respectively, so as to rotate the wheel clockwise in Fig. 1. The wheel 54 is of considerably greater diameter than is the disk 53.

The perimeter of the wheel 54 is provided with teeth so arranged that a pawl may be employed to rotate said wheel counterclockwise in Fig. 1 against the influence of the spring 55. The teeth are slightly greater in number than the maximum number of coins which the machine may be adjusted to deliver in a group. Thus the wheel is shown as having fifty-three teeth, of which fifty may be employed for rotating the wheel counter-clockwise while the remainder enable the locking pawl to prevent accidental clockwise rotation 45 of the wheel before the maximum number of

coins is delivered. The wheel is also provided with a perimetral notch having a radial shoulder or wall 56 facing clockwise while the other wall of the notch is angular thereto.

The upper end of the bent lever 43 has pivotally mounted thereon a pawl 57 which is pressed by a spring 57a to engage the toothed perimeter of the wheel 54 and as the lever 43 is rocked clockwise in Fig. 4 as it is when the roller 40 is elevated by a coin passing under the same, the pawl 57 moves the wheel counterclockwise the space of one tooth. The spring 49 retracts the pawl after each of its operative movements. 58 represents a gravity dropped locking pawl which is pivotally mounted on the outer protruding end of the bolt 50. The pawl drops down onto the tooth of the wheel 54 when the latter comes to rest after being moved forwardly by the pawl 57, and thus prevents the spring 55 from reversing the movement of the wheel. When the shoulder 56 is moved past the pawl 58 the latter drops down behind the shoulder and thus locks the wheel 54 stationary.

Intermediate of its ends the pawl 58 has pivotally attached thereto by means of the pin 59 the upper end of a link 60 whose lower end is pivotally connected to the upper end of a locking bar 61 which is pivotally attached at its foot to the side of the adjacent bearing member 16a. The bar 61 is provided with a notch 62 which when the link and lever are thrown into the position shown in Fig. 3 engages one of the teeth of the ratchet gear 63 mounted on the shaft 16 but the notch, when the link and lever are thrown into their positions shown in Fig. 1, is disengaged from said ratchet wheel.

The notch 62 may be thrown out of engagement with the ratchet wheel by means of a bent lever 64 pivotally attached at its angle to a portion of the frame plate 44 and having its lower end connected to the pivot connection between the link 60 and the bar 61 while its upper end protrudes through a slot in the rear wall 3 of the housing.

It is apparent that when the ratchet wheel has been advanced by means of the operation of the pawl 57 until the locking pawl 58 drops down behind the shoulder 56, the drop of the pawl will cause the link 60 to drop, thus engaging the notch 62 with the ratchet wheel 63, thereby locking the shaft 16 and preventing the rotation of the notched disk 12.

65 is a curved lever whose front end is pivotally mounted on the outer end of the bolt 50 and which extends over the protruding end of the pin 59 which attaches the pawl 58 to the link 60 and under a pin 66 which protrudes from the side of the pawl 57. The lever 65 is provided with a toe portion 67 which, when the lever is lowered, may rest on the disk 53.

It is obvious that when the link 60 and lever 61 are moved into their positions shown in

Fig. 1, disengaging the notch 62 from the ratchet wheel 63, the pawls 57 and 58 are raised from engagement with the ratchet wheel 54 and the latter will be free to be rotated clockwise in Fig. 1 by the expansion of the spring 55 to the limit of movement to which the apparatus has been adjusted.

The ratchet wheel 54 is provided on its outer face with a stud 68 which by coming in contact with the outer end of a stop arm 69 limits the clockwise rotation of the ratchet wheel 54 when the latter is released by the elevation of the pawls 57 and 58, as will be later explained.

The arm 69 is fixed to and disposed radially of a knurled knob 70 forming the outer end of a pin 71 which protrudes axially through the bore of the stud 51. The inner end of the pin 71 is threaded to receive a nut 72 and a spring 73 is wound about the pin between the inner end of the stud 51 and the nut 72.

The outer end of the arm 69 is provided with a lip 74 which fits into one of the notches 75 which are formed in the perimeter of the disk 53 and which is also engaged by the stud 68 on the ratchet wheel 54. Thus by pulling outwardly on the knob 70 to release the lip 74 from the notch 75 with which it is engaged, the stop arm 69 may be swung into position to engage any selected notches of the disk.

The side wall 2a of the housing is provided with an aperture 70a through which the knob 70 may be seized with the fingers and this aperture is wide enough to expose a portion of the arm 69 so that its angular position may be observed. The surface of the wall 2a about the aperture is graduated and marked to designate the number of teeth of the ratchet wheel 54 which will be engaged by the pawl 57 in moving the ratchet wheel while the stud 68 is traveling from its initial or retracted position against the end of the arm 69 to a position wherein the locking pawl 58 drops down behind the shoulder 56.

It is obvious that when the locking pawl 58 has dropped down behind the shoulder 56, the pawl 57 can no longer advance the ratchet wheel or rather after each forward push of the ratchet 54, the ratchet will be spring-returned until the shoulder 56 bears against the dropped pawl 58.

In operation the arm 69 by means of the knob 70 is turned to and engaged with the proper notch 75 on the disk 53 to provide for the retraction of the ratchet wheel 54 for the number of teeth corresponding to the number of coins which the machine is to deliver. The hand lever 64 is then pulled to release the notch 62 from the ratchet wheel 63 and to raise the pawls 57 and 58 from engagement with the ratchet wheel 54. The wheel 54 is now released and is spring-rotated clockwise in Fig. 1 until its stud 68 engages the arm 69, thus halting the wheel. The shaft 16 has been

now unlocked so that the notched disk 12 may be rotated by means of the crank 17, delivering coins past the roller 40 to the coin-port 20. The coins passing under the roller 40 rock the coin-lever 26, thus operating the counting device 47 and also causing the pawl 57 to advance the ratchet disk 54 counterclockwise one tooth for each coin passing the roller 40.

When the number of coins determined by the setting of the arm 69 have been counted and delivered, the locking pawl 58 drops down behind the shoulder 56, thus locking the ratchet wheel 54 against reverse or clockwise movement and also locking the shaft 16 and the coin-disk 12 against further rotation.

To provide for the proper throw of the outer end of the coin-lever 26 I prefer to provide an abutment 76 threaded through a bracket 77 carried by the plate 22 and arranged to be engaged by the outer end of the coin-lever 26 on its upper movements. By adjusting this screw the proper throw will be given to the recording mechanism and also to the pawl 57.

In case it is desired to simply count coins, tokens or the like without separating them into groups of predetermined numbers, the arm 69 is swung into the position indicated at zero when the arm will hold the ratchet wheel 54 retracted past its operative range with the pawls 57 and 58 opposite the notch in the perimeter of the ratchet wheel and thus the pawl 57 will not be able to engage and operate the ratchet wheel. However the operation of the coin-lever by the passing coins will cause the latter to be recorded on the device 47.

The coins are presented to the notched disk 12 by means of a hopper which is positioned at the lower portion of the housing 8 and is preferably mounted on the housing. Thus the hopper is provided with an arcuate flange 78 which fits against and is secured to the outer surface of the wall 8a of the housing, as by screws 79. The hopper is provided with a wall portion 80 which extends upwardly from the flange 78 and diverges from the disk 12 in the direction of the rotation of the disk, as shown in Fig. 6, that is from left to right. Rising from the top of the wall portion 80 are the outwardly flaring end walls 81 and the front wall 82. The lid 6 may be hinged to the top of the flaring front wall 82, and thus when the lid is opened and supported in its inclined position by the leg 7, the coins may be spilled on the lid and will slide down into the hopper and be presented to the notched disk 12. The throat of the hopper because of the divergence of the wall portion 80 permits the notched disk to shift the indiscriminately presented coins so that they may be readily picked up one at a time by the notches of the disk.

The delivery end of the spout 11, is direct-

ed downwardly and is preferably in a horizontal plane so that a coin-receiver may be removably mounted below such mouth.

Thus I have shown in Fig. 1 a supporting fork 83 secured to the wall 3 of the housing and a paper coin case 84, of cylindrical shape and closed bottom, supported on said fork by means of its top flange 85. When the case 84 has been filled or has received the desired number of coins, it is removed from the fork and its top crimped in or otherwise closed to retain the coins.

What I claim is:—

1. In a machine for the purpose described, the combination of a housing, a disk rotating in said housing and having notches formed in the perimetral edge of said disk to carry coins and the like, the carried coins protruding beyond the perimetral edge of the disk, means to feed the coins to said disk, a counting device, a lever, one end of the lever being operatively connected to the counting device whereby the latter is operated by the movement of the lever, the other end of the lever being in the path of the protruding edges of the coins carried by said disk, and means to regulate the path of movement of the coin-engaged end of the lever whereby it may be operated solely by a coin and the like of a selected diameter while the path of movement of the other end of the lever remains substantially constant.

2. In a machine for the purpose described, the combination of a housing, a disk rotating in said housing and having notches formed in the perimetral edge of said disk to carry coins and the like, the carried coins protruding beyond the perimetral edge of the disk, means to feed the coins to said disk, a counting device, a lever, one end of the lever being operatively connected to the counting device whereby the latter is operated by the movement of the lever, the other end of the lever being in the path of the protruding edges of the coins carried by said disk, and means comprising a movably mounted plate provided with a slot and a movably mounted bolt extending through said slot and forming the axis of said lever's movement whereby to arrange the movement of said lever to cause it to be operated solely by a coin and the like of a selected diameter.

3. In a machine for the purpose described, the combination of a housing, a disk rotatably supported in the housing, said disk being provided with notches in its perimetral edge to carry coins and the like, means to rotate said disk, means to feed the coins to the disk, a counting device, a lever operatively connected to the counting device whereby the throw of the lever causes the counting device to register a unit, one end of the lever protruding into the path of the coins carried by the disk so that the lever is periodically thrown by the coins as they pass the lever and

means for adjustably limiting the throw of said lever whereby the machine may be set to be operated solely by a coin and the like of a selected size.

4. In a machine for the purpose described, the combination of a housing, a disk rotatably supported in the housing, said disk being provided with notches in its perimetral edge to carry coins and the like, means to rotate said disk, means to feed the coins to the disk, a counting device, a lever operatively connected to the counting device whereby the throw of the lever causes the counting device to register a unit, one end of the lever protruding into the path of the coins carried by the disk so that the lever is periodically thrown by the coins as they pass the lever and means for adjustably limiting the movement of the coin-end of the lever whereby the machine may be set to be operated solely by coins and the like of a selected size.

Signed at Pittsburgh, Pa., this 1st day of June, 1931.

CHARLES D. HOWENSTINE.
